UNITED STATES PATENT OFFICE.

WILLIAM MORRIS MORDEY, OF WESTMINSTER, ENGLAND.

ELECTROMAGNETIC SEPARATION OR CONCENTRATION OF MINERALS.

Application filed April 2, 1920. Serial No. 370,865.

To all whom it may concern:

Be it known that I, WILLIAM MORRIS MORDEY, a subject of the King of Great Britain and Ireland, residing at the city of Westminster, England, have invented Improvements in or Relating to Electromagnetic Separation or Concentration of Minerals, of which the following is a specification.

This invention has reference to improvements in the electro-magnetic separation or concentration of minerals, and it has for its object to enable such separation or concentration to be effected in a more rapid, effective and cheaper manner than heretofore.

For this purpose, the invention consists, according to one way of carrying it into practice, in causing a stream of finely divided mineral material, in the form of pulp, to flow longitudinally through a relatively long and narrow inclined launder or trough, that may be slightly higher at one side than at the other, and is arranged on or over the parallel poles of an alternating current multiphase electro-magnetic system, and subjecting the stream to the action of the multiphase magnetic field set up by the electro-magnetic system in such a way that material which is responsive to the action of such a moving magnetic field (and which is hereinafter referred to for brevity and distinction as responsive matter) will become separated from the gangue or other material present which is not responsive to such field (and which is hereinafter referred to for brevity and distinction as inert matter) and be gradually swept by such magnetic field in a lateral direction to the higher longitudinal side of the said narrow launder whilst the inert matter will be caused by gravity to move gradually in the opposite lateral direction, that is to say, to the opposite or lower longitudinal side of the launder or trough. In this way, the responsive matter and inert matter, separated more or less completely from each other, will move simultaneously down the launder and be discharged at the lower end thereof into separate receptacles or be otherwise dealt with. The material instead of being in the form of pulp may, in some cases, be in the dry state. In this case the launder may need to be very steep to cause the material to move along it readily. The movement of the material may be assisted by imparting a

vibrating or jerking motion to the launder, particularly when the material is dry.

From the foregoing description it will be understood that the fundamental feature of the invention is the use of a long narrow launder, inclined longitudinally, and it may be, transversely, for the passage of the material, which, during its movement down such launder as a whole, is subjected to the action of a multiphase magnetic field emanating from a long narrow multiphase electro-magnet placed immediately under the launder. Such an arrangement may be regarded as a constructional unit. When the material to be treated exceeds the quantity that can be dealt with by such a unit, a number of such units may be used, preferably combined in one structure.

The nature and scope of the invention, based upon the above principle, will be readily understood from the following description with the aid of the accompanying drawings which illustrate, by way of example and diagrammatically, various ways of carrying the invention into practice. In these drawings, Fig. 1 shows partly in side elevation and partly in vertical section on the line I—I of Fig. 2, Fig. 2 in plan and Fig. 3 in cross section on the line III—III of Fig. 1, one example of apparatus suitable for carrying out the invention as above set forth. The drawings are diagrammatic and it is to be understood that they relate to apparatus that can be used for the treatment of pulp or of dry material. Fig. 4 shows partly in side elevation and partly in vertical section, a modification. Figs. 5, 6, 7 and 8 are similar views to Fig. 3, illustrating other modifications of the apparatus. Fig. 9 shows partly in side elevation and partly in vertical section and Figs. 10 and 11 in cross section, further modified constructions of apparatus for carrying out the invention. Fig. 12 is a part plan and Figs. 13 and 14 cross sections, illustrating still further modifications.

Referring to Figs. 1, 2, and 3, the mineral material to be treated, hereinafter referred to generally as material, and consisting of a mixture of inert and responsive matters, hereinafter respectively referred to as α and α' , in a finely divided condition and usually in the form of pulp, is fed at any suitable rate, as by a feeding device b , from a hopper

c on to one end of a series of relatively long and narrow launders *d*. These launders are shown in the example, as made of a flat-bottomed channel provided with a number 5 of longitudinal ribs or partitions *k* to form the relatively long and narrow launders *d*, which are made of non-magnetic and non-conducting material. The launders are inclined both in the longitudinal direction and 10 in the transverse direction to any required degree. The material is subjected, during its downward passage through the launders to the action of an alternating current multiphase electro-magnet *e* constructed of laminated iron and having upwardly projecting 15 poles or teeth *e*¹ which are parallel with one another and extend substantially the whole length of the launders. The spaces *e*² between the poles or teeth may be either open, as 20 shown, or of the closed type (see Fig. 5) or of the partly closed slotted type (see Fig. 14). The electro-magnet *e* is suitably magnetized by multiphase exciting windings *g*, *g* that are preferably disposed longitudinally between 25 the teeth and are connected in any appropriate manner, such that the movement or so called "rotation" of the field, due to the multiphase currents, will pass as a succession of alternating magnetic waves from one 30 side to the other across the face of the magnet at right angles to its length and to the length of the launders. As a consequence, any material in the launders capable of responding to the moving magnetic waves so 35 set up, will, as it moves down the launders *d*, pass transversely across the launders. The material, as a whole, passes down the launders under the action of gravity, assisted it may be, by any suitable method of 40 agitation, as by shaking, jerking or vibrating the launders, or the apparatus as a whole.

By tilting the launders and magnet as described, slightly at right angles to their 45 length, gravitational separating action may be combined with the electro-magnetic action. For example, if the moving magnetic field passes from left to right of the launders and if the tilting is such that the left sides of 50 the launders are slightly depressed, as seen in Fig. 3, the inert material *a* will gravitate towards the lower left hand side of each launder whilst the responsive matter *a*¹ will pass to the right hand side of each launder 55 under the influence of the said field although such action necessitates its moving up a slight incline from left to right if the launders should be slightly inclined transversely. Thus, during the passage of 60 the material as a whole down the launders, a separation or concentration will gradually take place, the matter *a*¹ leaving the right hand side of each launder *d* being different in composition to the matter *a* leaving the 65 left hand side of each launder. Adjustable

septums or dividing plates *h*, *h* may be provided, suitably to direct the discharged separated materials into appropriate receptacles, *i*, *i*¹, or for passing them on for further treatment. By using two septums such as 70 *h*, (Fig. 12) to each separate launder *d*, three grades of materials will be collected namely, heads, middlings and tailings, any or all of which may, if necessary, be subjected to further concentration by being passed 75 down the launder a second time or oftener, or successively down other launders.

Each launder is made narrow in order that the particles to be separated from the pulp shall have only a small distance to 80 travel transversely.

The strength of the magnetic action can be varied, as for example by varying the excitation, or the distance of the material from the face of the magnet in the successive treatments, or in successive launders. Thus, the more responsive matter may be first separated by a weak electro-magnetic induction, and afterwards, 85 the less susceptible material with a higher 90 induction.

The length of the launder and its slope, both longitudinal and transverse, will be determined by the nature of the material to be treated, the time necessary for concentration, and the strength of the field. 95

Suitable results can be obtained when treating feebly magnetic material in pulp form, by making the launder, or each launder, many feet long and only a few inches wide, for example, if in one continuous length, 20 to 40 feet long and 6 inches to 1 foot wide, with a longitudinal inclination of about 1 in 20 and a transverse inclination of about 1 in 30. 100

By first submitting the material to be treated to a strong magnetic induction, either alternating or direct current, the responsive portion will, with some materials, be made more sensitive or responsive to the multiphase field to which it is afterwards subjected, so that the separation and concentration of the material can be carried out with a lower excitation of the electro-magnet used for the purpose than would otherwise be the case. For this purpose, the preliminary induction may, for example, be applied by causing the material to pass through the field of one or more electro-magnets *m* arranged in the path of the material on its way to the upper end of the launders *d*, as shown in Fig. 4. The electro-magnet *m* may be one phase, or multiphase, or direct current; or permanent magnets may be used. The supporting means for such electro-magnet should be non-conducting for an alternating current magnet or magnets, or non-magnetic for a direct current magnet or magnets. 115

Instead of causing the separated respon- 120

sive matter a^1 to pass completely down the launder, that side of the launder to which it is moved, may be so arranged that such matter will be discharged from it in a lateral direction, the inert matter a passing longitudinally down the trough. This arrangement is shown in Figs. 5 and 6.

The windings g of the electro-magnet e , or their connections, may be so arranged that the magnetic movement of the responsive matter a^1 will be from the middle of a launder laterally in both directions to its opposite sides, so that the inert material a may gravitate to the middle of the launder and pass downwards and escape through a single discharge at the bottom of the launder while the responsive matter a^1 will pass to the two sides of the launder from which it can be discharged as indicated in Fig. 7. With such an arrangement, the launder and, it may be, the electro-magnet also, should be slightly curved at right angles to its length, as shown, so that the inert matter a can gravitate to the middle. Or, by providing the sides of the launder with raised edges, so as to prevent the responsive matter a^1 from passing over the sides of the launder, the said responsive matter can be caused to pass down the two side portions of the launder and be discharged at the lower end thereof.

The launder may have over it a laminated magnetic cover d^1 (Fig. 3), or a second magnet e^2 (Fig. 14) may be used having its poles or teeth projecting downwards and facing those of the lower magnet. This may increase the inductive action but does not affect the principle of the invention.

Instead of using a separate launder or launders, the material may be caused to flow longitudinally over the surface of the electro-magnet, where the spaces e^2 between the poles of the magnet are of the closed slot type, as in the example shown in Fig. 5. The surface of the magnet thus forms a launder. Or, alternatively, the electro-magnet may be supported with its poles extending downwards, the material being placed on a launder, below the poles, which may be formed by a plain laminated iron structure through which the magnetic circuits are completed, as in the examples shown in Figs. 6, 7 and 8. Or the launder may be of a non-conducting material.

The launder instead of being inclined, may be horizontal in its longitudinal direction. In either case, the material to be treated may be caused to move as a whole in either direction along it by the action of a succession of shocks or jerks imparted to the launder in a manner well known in connection with ore dressing machines, the responsive matter and inert matter passing transversely to opposite sides of the launder in the manner hereinbefore described. Fig. 1

shows, for example, a tapping lever r arranged to be oscillated by a rotary cam s and to impart shocks to the launder d .

Although it is advantageous to incline the launder sideways, or to make it concave, in order to cause the inert and responsive portions of the material respectively to move in opposite directions, the one by gravity and the other under the action of electro-magnetic induction, the launder may, in some cases, be horizontal in the transverse direction (see Fig. 11) and the inert matter be caused to move laterally in one direction by imparting a succession of shocks, jerks or the like to the launder whilst the responsive matter, notwithstanding such shocks, is moved by induction in the opposite direction. Or, in some cases, the launder may be inclined sideways as described and the electro-magnet e be so arranged (see Fig. 13) that the inert matter a will be caused to move laterally and in an upward direction by imparting shocks or jerks to the trough, whilst the responsive matter a^1 may be prevented from so moving or even be caused to move laterally in the opposite and downward direction by the electro-magnetic induction. In this case gravity assists electro-magnetic induction.

When treating dry material by the method described, the material may, as shown in Fig. 9, be carried through the multiphase electro-magnetic field by an endless belt n , driven by one or both of the pulleys o over which it works, the responsive matter a^1 moving laterally and being discharged in any of the ways hereinbefore described. Thus, by using the arrangement of a magnetic field moving from the middle to each side and by employing a concave belt, the responsive matter a^1 may, as shown in Fig. 10, be discharged over each side of the belt whilst the inert matter a at the centre of the belt, to which it would gravitate, can be discharged over the pulley at one end.

Or the belt n may, as shown in Fig. 11, be flat and be provided with longitudinal flexible ribs or divisions k , for the same purpose as those described with reference to Figs. 2 and 3, the separate products being discharged over the forward end pulley into suitable places or receptacles. In this case the belt and magnet will be inclined transversely. If necessary, the belt may, in each case, be shaken or agitated to facilitate the desired action.

In Fig. 3 the electro-magnet e is shown diagrammatically as provided with a winding suitable for two phase or three phase; Figs. 5, 6, 8, 11 and 14 for three phase; Figs. 7 and 10 indicate a two phase winding, one phase being applied to the middle pole or tooth and the other phase to the right and left hand poles or teeth.

From the foregoing examples it will be

seen that the principle of the invention can be carried into effect in various ways. It can be applied in connection with many forms and arrangements of ore dressing apparatus, such as shaking tables, vanners, classifiers and the like, for the purpose of assisting, augmenting or supplementing their action.

It will be understood that in some cases the object of separating the responsive matter may be to obtain purified or concentrated inert matter.

What I claim is:

1. The herein described method of effecting the electro-magnetic separation or concentration of finely divided mineral matter, said method consisting in causing such matter to pass longitudinally over a relatively long and narrow support arranged

adjacent to the longitudinal and parallel poles of an alternating current multiphase electro-magnet and subjecting the stream to the action of the multiphase moving magnetic field set up by the said electro-magnet

transversely to the said stream and support, the said support being of such length that material that is responsive to the action of such a magnetic field will become separated from the material that is not responsive to such field, and be gradually swept in a lateral direction by such moving magnetic field to one longitudinal side portion of the said support whilst the inert matter will be caused gradually to move in the opposite lateral direction to another longitudinal portion of the said support, the responsive matter and the inert matter being divided into separate streams that are separately discharged from said support.

2. In the method of separating or concentrating mineral matter according to claim 1, supporting the material in a transversely inclined plane to permit transverse gravitational deviation of one of the two portions of matter from the other portion.

3. In the method of separating or concentrating mineral matter according to claim 1, simultaneously agitating the material, substantially as described for the purpose set forth.

4. In the method of separating or concentrating mineral matter according to claim 1, causing the separated responsive matter whilst moving longitudinally to be moved laterally to one longitudinal side of the relatively long and narrow longitudinal support and be discharged laterally over such longitudinal side.

5. The herein described method of effecting the electro-magnetic separation or concentration of finely divided mineral matter, said method consisting in causing said matter whilst carried by a long and narrow support to pass longitudinally through and subjecting it to the action of a multiphase

moving magnetic field moving in a direction transverse to the said support and set up by an alternating current multiphase electro-magnet having poles arranged parallel and adjacent to the said support, said support being of such length that material that is responsive to the action of such a magnetic field will become separated from the material that is not responsive to such field, and be gradually swept in a lateral direction by such moving magnetic field to one longitudinal side portion of the said support whilst the inert matter will be caused gradually to move in the opposite lateral direction to another longitudinal portion of the said support, the responsive matter and the inert matter being divided into separate streams that are separately discharged from said support.

6. In the method of separating or concentrating mineral matter according to claim 5, subjecting the finely divided mineral matter to be treated, to a strong preliminary magnetic induction.

7. For carrying out the method of separating or concentrating mineral matter according to claim 1, apparatus comprising a long and narrow downwardly inclined support over which the mineral matter is caused to pass in the longitudinal direction, each of the longitudinal side portions of said support being at a higher level than an intermediate longitudinal portion of said support, and an alternating current multiphase electro-magnetic system having parallel poles arranged lengthways of and adjacent to said support so that the moving magnetic field set up by said electro-magnetic system will move transversely to said support in a direction to sweep responsive matter in the mineral matter towards one of the longitudinal sides of the support.

8. For carrying out the method of separating or concentrating mineral matter according to claim 1, apparatus comprising a long and narrow launder over which the mineral matter to be treated is caused to move in the longitudinal direction, said launder having its longitudinal edge portions higher than an intermediate longitudinal portion, and an alternating current multiphase electro-magnetic system having parallel poles arranged lengthways of and adjacent to said launder and adapted to set up multiple moving magnetic fields that will travel transversely in opposite directions towards the longitudinal sides of the launder.

9. For carrying out the method of separating or concentrating mineral matter according to claim 1, apparatus comprising a long and narrow launder over which the mineral matter to be treated is caused to move in the longitudinal direction, said launder having a bed of concave shape in

cross section and an alternating current multiphase electro-magnetic system having parallel poles arranged lengthways of and adjacent to said launder and adapted to

- 5 set up moving magnetic fields that will travel transversely to said launder and in opposite directions to one another to cause responsive matter separated from inert matter to be discharged over the opposite longitudinal edges of the launder whilst inert matter will be caused to travel along the lower longitudinal central portion of the launder.

10. For carrying out the method of separating or concentrating mineral matter according to claim 1, apparatus comprising a relatively long and narrow launder, inclined both longitudinally and laterally, and having its lower longitudinal side higher than an intermediate longitudinal portion of said launder and an alternating current multiphase electro-magnetic system having parallel poles arranged lengthways of and adjacent to said launder and adapted to produce a travelling field.

11. For carrying out the method of separating or concentrating mineral matter according to claim 1, apparatus comprising a relatively long and narrow launder, inclined both longitudinally and laterally and having both of its opposite longitudinal sides higher than an intermediate longitudinal portion and an alternating current multiphase electro-magnetic system having par-

allel poles arranged lengthways of and adjacent to said launder and adapted to create a travelling field. 35

12. For carrying out the method of separating and concentrating mineral matter according to claim 1, apparatus comprising 40 a long and narrow launder along which the mineral matter is caused to flow longitudinally, an alternating current multiphase electro-magnetic system having poles arranged lengthways of and adjacent to said 45 launder and adapted to create a travelling field and magnetic means adapted to magnetize said mineral matter preparatory to its being subjected to the moving magnetic field of said electro-magnetic system. 50

13. In apparatus for separating and concentrating mineral matter, a long and narrow launder inclined in the direction of its length and in a direction at right angles thereto, feeding means for delivering mineral matter on to one end of said launder, an alternating current multiphase electromagnet arranged with parallel poles lengthways of said launder and adapted to create a travelling field, means for subjecting said 60 mineral matter to a preliminary magnetization before it comes into the moving magnetic field of the said electro-magnet and means for imparting a shaking movement to said launder and mineral matter thereon. 65

Signed at London, England, this 16th day of March 1920.

WILLIAM MORRIS MORDEY.
